UNITED STATES PATENT OFFICE.

WILLIAM M. COBB, OF ZION, ILLINOIS, ASSIGNOR TO WILBUR GLENN VOLIVA, OF ZION, ILLINOIS, DOING BUSINESS UNDER THE FIRM NAME AND STYLE OF ZION INSTITUTIONS AND INDUSTRIES.

DESIGN FOR A CHILD'S VELOCIPED.

59,335.

Specification for Design.

Patented Oct. 11, 1921.

Application filed May 3, 1921. Serial No. 466,619. Term of patent 3½ years.

To all whom it may concern:

Be it known that I, WILLIAM M. COBB, a citizen of the United States, residing at Zion, in the county of Lake and State of Illinois, have invented a new, original, and ornamental Design for a Child's Velocipede, of which the following is a specification, reference being had to the accompanying drawing, forming part thereof.

The figure is a perspective view of a child's velocipede, showing my new design.

I claim:

The ornamental design for a child's velocipede, as shown.

WILLIAM M. COBB.
